UNITED STATES PATENT OFFICE.

JESSE V. SOUDER, OF JERSEY CITY, NEW JERSEY.

COMPUTING MECHANISM.

1,114,406.

Specification of Letters Patent. Patented Oct. 20, 1914.

Application filed May 28, 1912. Serial No. 700,146.

To all whom it may concern:

Be it known that I, JESSE V. SOUDER, a citizen of the United States, and a resident of Jersey City, in the county of Hudson and State of New Jersey have invented a new and Improved Computing Mechanism, of which the following is a full, clear, and exact description.

This invention relates to improvements in computing machines and is adapted to be used with any desired mechanism, as for instance it may be combined with a recording machine in the form of a typewriter and associated with the mechanism thereof, so as to be operated by the usual number keys provided on that kind of mechanism.

The object of the invention is to provide a structure in which the operating parts are reduced to a minimum, and the amount of energy or power required for operating the device is also reduced to a minimum.

A further object of the invention is to produce a computing device which may be operated in both directions, namely operated so as to add and operated so as to subtract.

In carrying out these objects a mechanism is provided which may be secured to a typewriter or other machine in any desired manner and which is constructed so as to occupy a minimum space. All the operating mechanism is arranged in a housing except the restoring and resetting members and part of the digit wheel. In forming the mechanism the same is designed to be operated by a master wheel, the master wheel operating through the various digit wheels, which in turn act at times upon mechanism provided which will cause the next succeeding digit wheels to be operated and to become locked when operated until released. Each of the digit wheels is associated with a restoring mechanism, a transfer mechanism, and a trip mechanism so that each succeeding digit wheel and associated mechanism is merely a duplication of the next digit wheel and associated mechanism, but a single restoring mechanism is provided designed to restore all of the digit wheels at any time so that a new addition or computation may be made.

A practical embodiment of the invention is represented in the accompanying drawings forming a part of this specification, in which similar characters of reference indicate corresponding parts in all the views.

Figure 1 is a view of the restoring mechanism and associated parts, together with part of the casing; Fig. 2 is a view similar to Fig. 1, except that the mechanism is shown moved to another position; Fig. 3 is a side elevation of the device with the side plate removed; Fig. 4 is a view similar to Fig. 3 except that part of the front mechanism has been removed for illustrating the action of the trips and transfer levers; Fig. 5 is a section through Fig. 3 on the line 5—5; Fig. 6 is a section through Fig. 5 on the line 6—6; Fig. 7 is a section through Fig. 5 on the line 7—7; Fig. 8 is a side elevation of one of the trip levers; Fig. 9 is a side elevation of one of the drivers and transfer levers associated with a trip lever shown in dotted lines; Fig. 10 is a view similar to Fig. 9 except that the trip lever is shown tripped; Fig. 11 is a side view of a transfer lever lock; Fig. 12 is a side view of a comb-like collector; Fig. 13 is a side view of a digit wheel shaft; Fig. 14 is an edge view of one of the centering pawls; Fig. 15 is a transverse sectional view through the rocking comb shown in Fig. 12 and the shaft shown in Fig. 13 in assembled position; Fig. 16 is a view similar to Fig. 15 except that the same shows a slightly modified form of the invention; and Fig. 17 is an edge view of part of the resetting mechanism together with a segmental rack forming part of the restoring mechanism. Fig. 18 is a fragmentary view showing a driver and trip lever together with associated parts, the structure being shown in its inoperative or neutral position; Fig. 19 is a view similar to Fig. 18 except that the parts have been moved to a tripped position, such position being assumed when the device is adding; Fig. 20 is a view similar to Fig. 18 except that the parts have been tripped to the position occupied when subtracting, the various parts being shown in dotted lines in the adding position.

Referring to the accompanying drawings by numerals, 1 indicates a housing provided preferably divided centrally on the line 2 and thus providing a cap or covering 3 which may be held in place in any desired manner, as for instance by suitable screws. The housing 1 is provided at one end with a projection 4 designed to co-act with a hook end 5 of a reciprocating catch 6. The catch 6 is provided with a roughened or corrugated surface 7 for being easily engaged by the thumb and finger when it is desired to

move the same longitudinally. The catch 6 is formed with slots 8 which accommodate pins 9 mounted in a pivotally mounted handle 10. A spring 11 is connected with the handle 10 and with the catch 6 so as to normally hold the same in the position shown in Fig. 1. The handle 10 is rigidly secured to a shaft 12 which projects a short distance into the housing 1 and has rigidly secured thereto a segmental member 13 which acts as a cam against a shoulder 14 formed on a plate 15. The plate 15 is provided with a slot 16 designed to accommodate a pin 17 which is connected to the housing 1 and remains stationary but permits the plate 15 to reciprocate back and forth. The plate 15 has a turned up portion 18 which forms a shoulder 19 designed to engage lugs 20 extending from the resetting slides or drivers 21 hereinafter fully described. The turned up portion 18 extends forwardly and carries a pivotal pin 22 at its forward end to which is pivotally connected a plurality of transfer lever locks 23 hereinafter fully described. The segmental cam 13 is provided with a pin 24 which extends upwardly through a pivotally mounted plate 25 having gear teeth 26 on the outer end which consequently acts as the segment of a gear and is adapted to mesh with a pinion 27 rigidly connected with a gear wheel 28. The gear wheel 28 is designed to mesh with a pinion 29, which in turn meshes with a gear wheel 30 mounted on a shaft 46, which is designed to carry the various digit wheels hereinafter fully described. In order to permit a proper rocking motion of the pin 24 around the shaft 12, a slot 32 is provided, merging into a substantially arc-shaped slot 33. When the device is positioned as shown in Fig. 1, a partially rotary movement of the handle 10 and associated parts, which includes the pin 24, will merely cause the pin 24 to move from one end of the slot 33 to the opposite end without affecting the position of the plate 25. However, this movement has caused a rearward movement of the plate 15 and associated parts which will result in a movement of the levers 23 and also other movements of other parts, as will be hereinafter fully described. As the pin 24 continues to move or rotate, the same will press against one of the walls of the slot 32 and will gradually move through slot 32 until it has reached the position shown in Fig. 2. This later movement of the pin 24 will cause a swinging movement of the plate 25 and consequently will cause a rotary movement of the pinion 27 and connected parts so as to restore the digit wheels to their original position with the zeros arranged opposite the opening 34 in the casing 1. A reverse movement, namely a reverse movement of the various parts when the lever or handle 10 is brought from the position shown in Fig. 2

back to the position shown in Fig. 1, will of course cause a reverse movement of the various pinions and gear wheels, but will not affect the digit wheels, as hereinafter fully described, nor will it cause a permanent 70 change in the position of any of the other parts of the device.

The various digit wheels 35, 36, 37 and 38, are made identical in construction and are provided with reference numerals arranged 75 between the teeth positioned thereon, the numerals being from zero to nine. Only four of these wheels are shown in the drawings, and in the mechanism space is provided for operating four, although it will be evident 80 that a greater or less number of digit wheels may be provided without departing from the spirit of the invention, the number of these parts being merely a matter of duplication. All of the teeth of each of the digit 85 wheels are cut away for forming an open space at one side of the respective teeth, except the master or controlling teeth 40 which are formed the full width of the respective digit wheels. Each of these wheels 90 is formed with an annular recess 41 in which is positioned a pin 42 designed to be engaged by one of the collecting projections 43 of comb 44. The comb 44 is designed to rest in a groove 45 in shaft 46 so that the 95 collecting projections 43 may at certain times fit in grooves 47 in the shaft 46. A projection or stop 48 is provided which is adapted to fit into a friction ring 49 mounted on the shafts 46. The friction ring 49 is provided with notches 50 and 51 designed to at various times engage a pivotally mounted pawl 52 resiliently pressed against the periphery of the friction ring 49 by a suitable spring member 53. The pawl 52 is adapted 100 to cause a positive stop upon the rotation of the friction wheel or ring 49 and associated parts. When the handle or lever 10 is moved over to the position shown in Fig. 2, the shaft 46 is rotated as the same is keyed to the gear wheel 30. The movement of the gear wheel 30 is only sufficient to turn the friction ring or wheel 49 nine-tenths of the distance around a circle, or from notch 50 to the notch 51. This movement will restore 105 all of the digit wheels to their original position and a reverse movement of the handle or lever 10 from the position shown in Fig. 2 to that shown in Fig. 1, will cause a reverse movement of the wheel 49, but will not cause 110 any movement of the digit wheels, the same being resiliently held against movement by pawls 54. The stop or projection 48 of the comb 44 fits into a suitable notch in the wheel 49 so that when the wheel 49 is rotated by the shaft 30 and associated parts, the same will first rock the comb 44 so that the collecting projection 43 will be moved 115 into the path of the pin 42 and then will bodily move the comb 44 in a rotary direc- 120

125

130

tion, collecting the various pins 42 and digit wheels connected therewith until a zero of all the digit wheels is brought opposite the opening 34 whereupon the gear wheel 30 and associated parts have reached their extreme position. The reverse movement of the gear wheel 30, friction wheel 49, and comb 44 will not affect the position of the digit wheels as in case the collecting projections strike the pins 42 they will merely be depressed into the grooves 47 and in fact the first part of the movement of the wheel 49 will cause the depression of these members. A reverse movement of the handle or lever 10 from the position shown in Fig. 2 to the position shown in Fig. 3 will cause a rotation of gear wheel 30, shaft 46, the friction ring or wheel 49 being held by pawl 52 until the collecting projections 43 are depressed within the groove 47, when stop 48 acts as a key for turning ring 49 back to its normal position, or from notch 51 to notch 50 whereupon notch 50, pawl 52, will be again engaged, thus holding the collecting projections 43 firmly within the grooves 47. In connection with the comb 44 and associated parts, attention is called to Fig. 16 in which a slightly modified form of comb 44' is provided in which the collecting projections 43' are formed with hook ends 55 which are designed to engage the respective pins 42 and collect the same in a similar manner to the way the comb 44 collects the pins. It will also be noted that the collecting projections 43' extend in an opposite direction to the way the collecting projections 43 extend, as the same pull on the pins 42, while the collecting projections 43 press against the pins or push the same.

When the master wheel 56, or any other device has operated digit wheel 35 for instance, (it being assumed to be at zero) until the same has been moved for a complete revolution, or ten times. Upon the tenth movement of the digit wheel the tooth 40 will strike against the end 57 of the trip lever 58 and move the same pivotally, as shown in dotted lines in Fig. 10, and in elevation in Fig. 4. The trip lever 58 is mounted on a stationary shaft 59 positioned in the casing 1 and cap 3. The trip lever 58 is provided with a slot 60 merging into an opening 61 having oppositely disposed walls 62 and 63 and oppositely disposed walls 64 and 65. At the end of lever 58 opposite slot 60 is a substantially U-shaped opening. This opening includes a rear socket 66, diverging slots 69 and 70, and slightly converging slots 67 and 68 whereby a central tongue 71 is provided, having a substantially squared end 72. When one of the master teeth 40 engages end 57 and moves the trip lever, end 72 will move from in front of pin 81 and as this pin is being urged forward by its driver, the same will engage one of the walls 71' and cause the pivotal movement of the lever 58 to continue until the same has reached the position shown in dotted lines in Fig. 10. As pin 83 is connected with the lever 58 the pivotal movement of lever 58 will cause pin 83 to engage and press against one of the walls of the slot 60 so that the transfer lever is swung to one side as the driver moves the same forward. When the trip lever is reset a reverse action is caused. When the driver is being moved back, the pin 81 engages the outer walls of slots 67 and 69 or slots 68 and 70 according to the direction of movement of the lever 58. The pin 81 follows these walls until it reaches socket 66 and then moves against end 72, this last movement taking place when the resetting mechanism is released. During the time that pin 81 is in socket 66 the trip levers 73 are positively locked or held against pivotal movement by said pin, whereby the various denominational wheels cannot move past zero under the action of momentum. This is true of all the wheels except one denominational wheel which is engaged and locked against passing the zero point by lever 97 shown in Fig. 3. One side of the trip lever 58 is formed with an enlargement 73 having a plurality of notches 74 formed therein for engaging a trip locator 75 which is substantially a pivotally mounted pawl acted upon by a retractile spring 76. The trip locator 75 is pivotally mounted on a shaft or pin 77 and is designed to continually engage one of the notches 74 under the action of the spring 76 which is connected to a projection 78 at the rear of one of the drivers 21. Upon the movement of the tenth cog or tooth of the digit wheel 35 the trip lever 58 will be tripped or moved pivotally as above described and will remain in that position until reset. The pivotal movement of the trip lever 58 will cause several other parts to operate, as various mechanism is provided which project into some of the grooves or slots formed in the ends of the trip lever. One of the functions of the trip lever 58 is to release its co-acting driver 21, more clearly illustrated in Figs. 5, 9, and 10. The driver 21 is formed with a slot 80 for accommodating the shaft 17 positioned stationary in the housing 1. The driver 21 is also provided with a pin 81 which, if desired, may be provided with an antifriction roller and which is adapted to fit into the socket 66 at certain times but to normally rest against the tongue 71 on the trip lever 58. The respective springs 76 not only hold the trip locator 75 in position, but also act on the drivers for giving the same a continuous tendency to move forward or toward the digit wheels. When the trip lever 58 has been moved in either direction, the pin 81

will move correspondingly, namely, into the passageways or slots 67 or 68, and from thence into the passageways or slots 69 or 70. Upon a longitudinal movement of the driver 21, pivotally mounted transfer lever 82 will be moved forward and at the same time swung to one side by the action of the trip lever 58, as heretofore described. The transfer lever 82 is pivotally mounted at 84 to the driver 21 and is preferably formed so that the outer surface thereof will be flush with the outer surface of the driver 21. Upon the forward and pivotal movement of the transfer lever 82 the same will strike 15 against one of the teeth of the next denominational wheel and cause the same to be moved one step forward. The driver 21 and associated parts will remain in this position until reset whereby the digit wheel 36 20 will be locked against movement in either direction as the point of the transfer lever 82 is against one tooth and the side of the transfer lever is resting against the next succeeding tooth, as clearly shown in Fig. 4.

In order to reset the driver, trip levers, etc., an arm or cam member 85 operated by the typewriter or other machine to which the device is connected, engages a stop or projection 86 and moves the same longitudinally of the casing 1 and consequently 25 moves the resetting mechanism hereinafter fully described for moving the drivers and associated parts to the position shown in Figs. 3 and 5. This resetting mechanism 30 will reset either one or all of the drivers and associated parts simultaneously. The stop or projection 86 is provided with a lug 87 rigidly secured by any means to the turned up portion 18 of the plate 15 so as to move 35 the plate 15 back and forth. The lug 87 has mounted therein a screw 88 which carries an antifriction roller 89 against which the cam 85 presses so as to reduce the friction to a minimum. A retractile spring 90 is connected at one end to the lug 87 and at the 40 opposite end to a stop 91 rigidly secured to the casing 1 in any desired manner. In order to properly guide the lug 87, a rod 92 is rigidly secured thereto and is arranged to slidingly fit in a suitable aperture in the stop 91 so as to be able to reciprocate back and forth therein. The cam 85 is designed to move the lug 87 in one direction and the spring 90 is designed to move the 45 same in an opposite direction so that shoulder 19 will be continually out of the way of the steps or projections 93 unless positively acting thereon for resetting the driver. This is necessary as when any of the trip 50 levers are operated the drivers could not move unless the shoulder 19 was out of the way. The shoulder 19 is adapted to engage any or all of the drivers according to whether or not the same has been moved 55 forwardly for resetting the same. By this

construction and arrangement it will be observed that the drivers are reset by an actuation of the stop or projection 86 and also reset by the member 13 which is rigidly connected with the handle or lever 10. When it 70 is designed to restore the digit wheels to their original position the lever 10 is operated and the first mechanism moved thereby will be the member 13 for causing a resetting of the drivers and after the resetting 75 of the drivers has been assured the mechanism will be operated as heretofore described for restoring the digit wheel. When the device is being operated for adding or subtracting, the resetting mechanism 80 is operated for resetting the drivers without affecting the position of the digit wheel. It will be evident that as all of the drivers, transfer levers, and trip levers are of identical construction, the description heretofore 85 given of one will apply equally to all. The forward end of the turned up portion 18 carries a pin 22 which in turn pivotally carries the transfer lock lever 23 pivoted at its upper end on the pin 77. The transfer 90 lock lever 23 is formed with a notch 95 designed to engage the respective pins 83 and positively lock the transfer levers 82 against pivotal movement but not against longitudinal movement. 95

From Figs. 5 and 7 it will be observed that the trip levers and the transfer levers are guided and in a certain sense held properly in position by a guide plate 96 formed with slots which permits a pivotal movement of 100 the trip levers and the transfer levers, but does not permit any lateral movement. The trip levers are designed to project a short distance beyond the plate 96 in order to be in the path of movement of the master teeth 105 40, whereby the same is moved pivotally and thus releases the drivers for causing the transfer levers to be moved pivotally and longitudinally for rotating the next succeeding wheel. 110

In order to provide a lock for the digit wheel 38, a pivotally mounted lock lever 97 is provided pivoted to the upper end of the shaft 59 and actuated by the end of the pin 22 operating in the slot 98. On the first 115 part of the movement of the resetting mechanism the pin 94 will move the lever 97 upward until the end 99 is in line with the ends 57 of the trip levers whereby the digit wheel 38 is locked against complete rotation or over restoring. 120

By the mechanism described it will be noted that a single mechanism is presented which is adapted to do double work, namely to add when moved in one direction, and 125 subtract when moved in an opposite direction. It will also be noted that the digit wheels are given a positive forward movement and a disconnected or free return, or rather the restoring mechanism therefor is 130

given this movement. When the handle or lever 10 is moved from the position shown in Fig. 3 to the position shown in Fig. 2, the digit wheels are positively rotated, but 5 when the handle or lever 10 is moved back from the position shown in Fig. 2 to the position shown in Fig. 3, the digit wheels are released or disconnected and the handle or lever 10 and associated parts are permitted 10 a free return movement. This is provided by the construction of the rocking comb 44 shown in Fig. 12 and the arrangement of the wheel staff or shaft shown in Fig. 13, wherein the fingers 43 of the comb 15 are permitted to rest in grooves on the return movement and are caused to move outward into the path of movement of the pins 42 when the wheels are being positively moved or restored. In regard to the single 20 mechanism doing duplex work it will be observed that each driver with its trip lever and transfer lever is designed to operate in a similar manner regardless of the direction of rotation of the digit wheels, with the exception 25 of the movement of the transfer levers and trip levers which swing in one direction when the digit wheels are used for adding, and swing in an opposite direction when the digit wheels are used for subtracting. 30

In operation, assuming that all of the denominational wheels are disclosing zeros through the opening 34, and it is desired to add 53, the master wheel 36, or any other 35 desired mechanism not forming any part of the present invention, is operated for causing the denominational wheels 35 and 36 to move, wheel 35 moving for three points or a distance of three teeth, and wheel 36 moving 40 for a distance of five teeth, thus disclosing instead of zero, the number 53. After the numeral 53 has been thus disclosed to view and it should be desired to add eight to fifty-three, the wheel 35 is rotated for a 45 distance of eight teeth. This will cause the numeral 1 to appear in the opening 34 on wheel 35, and will cause various mechanism to be operated for transferring motion to wheel 36 for moving the same a distance of 50 one tooth so that 6 will appear through the opening 34 on the wheel 36, thus resulting in the disclosing of the numerals 61. During 55 the rotation of wheel 35 and as the same moves so that the numeral 9 will leave opening 34 and zero will appear, the master tooth 40 of the wheel 35 will engage its transfer lever end 57 of the trip lever 58. The movement or tripping of the lever 58 will cause the member 71 (Fig. 9) to move 60 from in front of pin 81. This will allow one of the springs 76 connected with the driver 21 of the particular trip 78 which has been operated, to be released and allow the driver to move forward. The forward movement

of driver 21 in this manner will cause a forward and pivotal movement of lever 82. The lever 82 when moved in this manner will strike against one of the teeth of wheel 36 and move the same forward the distance of one tooth and lock the same in that position until the driver and trip just operated has been reset. In case it should be desired to add one hundred or more to the sum already found, wheel 36 or any of the higher 65 wheels may be operated and when the numeral 9 is about to leave the opening 34 and zero is about to appear, the master wheel of the respective wheel or wheels being operated will trip their respective trip levers 58 and cause a proper movement of the respective 70 drivers 21 and transfer levers 82. The tripping of the levers 58 by the wheel 35 eventually causes the proper operation of the transfer lever 82 as just described for the next succeeding higher wheel and this operation, of course, is repeated on all of the 75 wheels of the higher denominations. After the sum desired has been secured, as for instance the sum 61, and it is desired to subtract any number therefrom, a reverse movement of the denominational wheels may be caused which will cause a lesser number to appear opposite opening 34 and thus result in the operation of subtraction. For instance, if it is desired to take one from sixty 80 one, the wheel 35 is rotated in a reverse direction so that the designation zero will appear at opening 35 instead of numeral 1. After the number 60 has been thus secured, and it is desired to subtract five therefrom 85 wheel 35 is rotated in a reverse direction a distance of five teeth. As zero is presented to opening 34 the first movement of rotating the wheel 35 for five teeth will cause the master wheel 40 thereof to engage the same 90 trip lever 58 engaged while adding, but will cause the same to be tripped or moved pivotally in an opposite direction. This will release the driver associated with that particular trip and will cause the transfer lever 52 95 to move pivotally in an opposite direction to that when the adding operation was performed, whereby the wheel 36 will be rotated or driven for a distance of one tooth 100 in an opposite direction to the way it was driven for the operation of addition. The movement of the wheel 36 for a distance of one tooth will cause the numeral 5 to appear thereon opposite opening 4, and the rotation 105 of the wheel 35 for a distance of five teeth 110 will cause the numeral 5 to appear opposite the opening 5 on the wheel 35 and thus disclose the number 55 which is the number or answer sought. From this it will be seen 115 that the trips and the transfer levers operate 120 in different directions according to the direction of rotation of the respective denominational wheels. 125

Having thus described my invention I claim as new and desire to secure by Letters Patent:

1. In a computing device, a series of denominational members, a trip lever for each of said denominational members except the highest set in motion thereby, a transfer lever for each of said trip levers, adapted to be swung in either direction from a neutral position thereby, and a single actuating member released by each said trip levers for moving forwardly said transfer levers whereby said transfer levers will move the next higher denominational member.
2. In a computing mechanism, a series of denominational members, a pivotally mounted trip lever for each of said denominational members except the highest, the respective trip levers being operated by the respective denominational members, a driver for each of said trip levers, a transfer lever pivotally mounted on each of said drivers, means loosely connecting said transfer levers and said trip levers whereby the swinging movement of the transfer levers is controlled as the transfer levers move the next higher denominational member.
3. In a computing mechanism, a series of denominational members each of which is formed with a master tooth, a trip lever for each of said denominational members, except the highest, a transfer lever for each of said denominational members, a guiding grid formed with a slot for each of said trip levers and for each of said transfer levers for guiding one end of said trip levers into the path of movement of said master teeth whereby they are actuated thereby and for guiding said transfer levers so that upon each actuation they will engage the next highest denominational member and move the same one step, means for moving said transfer levers forwardly, and a pin for conveying motion from said trip levers to said transfer levers whereby said transfer levers will have a lateral as well as a forward movement.
4. In a computing mechanism, a series of denominational members, a reciprocating driver for each of the denominational members except the lowest, a transfer lever pivoted to each of said drivers and movable therewith, a pivotally mounted trip lever actuated by said denominational members, and pins on the transfer lever connecting said trip levers and said transfer levers whereby the swinging movement of the transfer levers is controlled as the drivers move the transfer levers longitudinally.
5. In a computing mechanism, a series of denominational members, a plurality of trip levers, a locator for each trip lever, a plurality of drivers normally pressing against said trip levers, a plurality of transfer levers, and means for conveying motion from said trip levers to said transfer levers whereby the transfer levers are swung to one side when said trip levers have been tripped.
6. In a computing mechanism, a series of denominational members, a transfer lever for each of said denominational members except the lowest, means for causing a swinging action of said transfer levers, a driver for each of said transfer levers for bodily moving the same during their swinging movement, each of said drivers being formed with a pair of spaced slots, a stationary pin extending through each of said slots for causing said drivers to move longitudinally, resilient means for moving said drivers in one direction, and resetting mechanism for moving the drivers in the opposite direction.
7. In a computing mechanism, a series of denominational members, a transfer lever for each of said denominational members except the lowest, a driver for each of said transfer levers for operating the same, each of said drivers being formed with a pair of guiding slots and a laterally extending hook member, stationary means extending through each of said slots for guiding said drivers in their movements, means for forcing said drivers in one direction, and reciprocating means engaging said hook members for moving the drivers in the opposite direction.
8. In a computing mechanism, a series of denominational members, a transfer lever for each of said denominational members except the lowest, a trip lever for each of said denominational members adapted to be operated thereby, a driver for each of said transfer levers, means pivotally securing said transfer levers to the respective drivers whereby the transfer levers are bodily moved whenever the drivers are moved, means projecting from each of said transfer levers into the path of movement of the respective trip levers whereby when the trip levers are moved the transfer levers will be moved pivotally, resilient means for moving the drivers in one direction, and a resetting mechanism for moving the drivers in the opposite direction.
9. In a computing mechanism, a series of denominational members, a transfer lever for each of said denominational members except the lowest, a pivotally mounted trip lever for each of the transfer levers, each of said trip levers being formed with an aperture merging into a slot, a reciprocating driver for each of said transfer levers, means pivotally connecting one end of the transfer levers to one end of the respective drivers, a projection extending from each of said transfer levers fitting in the apertures of the respective trip levers but not filling said apertures.

whereby said trip levers may move pivotally a short distance independent of the transfer levers, means for moving said drivers simultaneously with the trip levers whereby the transfer levers are given a direct longitudinal movement and then a combined longitudinal and pivotal movement, the projection extending from the transfer levers acting in said slot for causing the trip levers to swing the transfer levers, and resetting means for resetting the drivers, trip levers and transfer levers.

10. In a computing mechanism, a series of denominational members, a transfer lever for each of said denominational members except the lowest, a pivotally mounted trip lever for each of said transfer levers, each of said trip levers being formed with a plurality of notches on one side, a trip lever locator adapted to project into one of said notches, means for resiliently and yieldingly holding the locator in engagement with one of said notches for yieldingly resisting movement of the trip levers, and means for moving said transfer levers.

11. In a computing mechanism, a series of denominational members, a trip lever for each of the denominational members except the highest formed with a plurality of notches on one side, said trip levers being adapted to move pivotally in either of two directions, a locator for each of said trip levers yieldingly and resiliently engaging said trip levers in said notches for normally holding the levers in any of their various positions, a pivotally mounted transfer lever for each of the trip levers, and means connecting the transfer levers with the trip levers for causing the transfer levers to be moved pivotally in the same direction and substantially at the same time as the trip levers whereby the denominational members are operated in either direction.

12. In a computing mechanism, a series of denominational members, carrying mechanism therefor including drivers formed with a projection, a resetting mechanism formed with a reciprocating plate having a turned up shoulder designed to engage said projection for moving said drivers in one direction for causing the resetting of said carrying mechanism, and means for automatically restoring said resetting mechanism when released.

13. In a computing mechanism, a series of denominational members, carrying mechanism therefor, restoring mechanism for the denominational members and resetting mechanism for the carrying mechanism, said resetting mechanism including a reciprocating plate formed with a projection engaging part of the said carrying mechanism for operating the same, an extension projecting from the reciprocating plate, a spring engaging said extension and normally holding

the same in a predetermined position, means connected with the opposite end of the spring for causing the spring to continuously pull on said extension, and a guiding bar associated with said extension for guiding the same in its reciprocatory movement.

14. In a computing mechanism, a series of denominational members, carrying mechanism for the denominational members, restoring mechanism for restoring the denominational members, and resetting mechanism for operating said carrying mechanism for resetting the same after any operation thereof, said resetting mechanism comprising a reciprocating member provided with an extension, a rod rigidly secured to said extension, a post formed with an aperture for accommodating said rod whereby the rod is guided in its reciprocatory movement, and resilient means connected to said post and to said extension for normally holding the extension and parts connected therewith in an inoperative position.

15. In a computing mechanism, a series of denominational members formed with a plurality of projections and a pivotally mounted comb structure arranged to engage said projections when moved in one direction, carrying mechanism and restoring mechanism for the denominational members, said restoring mechanism including a cam connected to the shaft of the denominational members, said shaft carrying said comb shaped structure, a pivotally mounted arm, a train of gearing, a pivotally mounted rack engaging said train of gearing, and means connecting said rack and said arm whereby said rack is moved when said arm is shifted from one position to another.

16. In a computing mechanism, a series of denominational members, a shaft for supporting the same formed with a longitudinal groove and a plurality of substantially transverse grooves radiating from the longitudinal groove, a substantially comb-shaped structure pivotally arranged in said groove with the teeth thereof in the transverse grooves, a pin projecting from each of the denominational members arranged in the path of movement of the teeth of said comb-shaped structure when the same is moved pivotally out of said transverse grooves, a pinion secured to said shaft, means for operating the same, and means for retarding the movement of the comb-shaped structure.

17. In a computing device, a series of denominational members, a carrying mechanism therefor including trips operated by the denominational members, transfer levers, and means connecting the transfer levers and said trips for causing the trips to move each of said transfer levers in either of two directions whereby the denominational members are caused to add and sub-

tract at will, and a resetting member arranged to operate the transfer levers without disturbing the denominational members.

18. In a computing device, a series of denominational members, a pivotally mounted trip for each of said denominational members except the highest designed to be swung in either of two directions by said denominational members, a bodily reciprocating transfer lever, pins for connecting said transfer lever and said trip levers whereby the transfer lever will be moved pivotally in the same direction as the trip levers, said transfer lever being designed to engage said denominational members to cause the same to move in either of two directions for adding and subtracting at will, and means for resetting said transfer lever and said trip levers.
19. In a computing device, a series of denominational members, a plurality of trips, a plurality of transfer levers adapted to be swung in either of two directions from a neutral position, a driver for each of said transfer levers, resetting mechanism for resetting all of said drivers and transfer levers, and a locking lever for each transfer lever formed with a cam-shaped opening for locking said transfer levers in said neutral position after the levers have been reset.

20. In a computing device, a series of denominational members, a plurality of trips, a transfer lever for each of said trips, said trips and said transfer levers being adapted to be swung in either of two directions, a driver for each of said transfer levers, a pin projecting outwardly from each of said transfer levers, resetting mechanism for resetting said drivers, trips, and transfer levers, and a pivotally mounted transfer lever lock formed with a notch having outwardly curved sides adapted to engage the respective pins on said transfer levers for collecting and locking the transfer levers in a neutral position.

21. In a computing device, a series of denominational members, a plurality of trips, a plurality of transfer levers actuated by said trips, a driver for each of said transfer levers, resetting mechanism for resetting said drivers, trips and transfer levers, restoring mechanism for restoring said denominational members, means operated by said restoring mechanism for causing said trips to be held against movement whereby the denominational members associated therewith will be locked against movement beyond a certain extent when the same are restored, and a pivotally mounted member actuated by said transfer resetting mechanism for locking the denominational member not locked by said trips.

22. In a computing device, a series of denominational members, carrying mechanism therefor, restoring mechanism for said de-

nominational members, means acting on said carrying mechanism for causing the same to act as locks for some of said denominational members for preventing the same turning beyond a certain extent when said restoring mechanism is operated, and a pivotally mounted stop for locking the remaining denominational member against a predetermined movement when the restoring mechanism is operated.

23. In a computing device, a plurality of denominational members, a plurality of pivotally mounted trips formed with a substantially U-shaped slot in one end, a transfer lever for each of said trips, a driver for each of said transfer levers, a pin extending from each of said drivers into said substantially U-shaped slot, said pin acting against one wall of said slot for moving pivotally said trips when said driver is being forced forward and acting on the opposite wall for bringing said trips back to their original position when said driver is moved rearwardly, means for resetting said driver, and means for restoring said denominational members.

24. In a computing device, a series of denominational wheels, each of said wheels having an enlarged tooth, a pivotally mounted trip lever for each of said denominational wheels, a transfer lever designed to be moved pivotally by said trip levers, said trip levers normally projecting into the path of movement of said enlarged teeth whereby upon each rotation of any of the denominational wheels the trip lever associated therewith will be operated for swinging the transfer lever on its pivotal support, and a driver normally acting on each of said transfer levers for moving the same forwardly after the same have been moved pivotally by the trip levers, whereby the complete rotation of any of the denominational wheels except the highest will cause one of the trip levers and one of the transfer levers to actuate the next higher denominational wheel.

25. In a computing device, a series of denominational wheels, each of said denominational wheels being formed with a stop, a shaft for supporting said denominational wheels, said shaft being formed with a groove having radiating notches, a comb-shaped structure arranged in said groove with the teeth of the comb normally in said notches, means for rotating said shaft, means for raising the teeth of said comb at the beginning of the rotation of said shaft whereby the teeth of said comb will engage projections on said denominational wheels and move the denominational wheels until the enlargements arranged thereon are all in line, carrying mechanism, and a resetting member arranged to reset the carrying mechanism without disturbing the denominational wheels.

26. In a computing mechanism, a series of

denominational wheels, carrying mechanism for said denominational wheels including a transfer lever, a resetting member for resetting said transfer lever without disturbing the denominational wheels, a shaft for supporting said wheels and on which said wheels are loosely mounted, each of said denominational wheels being formed with a stop and said shaft being formed with a recess, a collecting comb formed with a body and a plurality of teeth arranged in said recess, means for rotating said shaft for resetting said denominational wheels, and a friction member connected with the body of said comb for 10 rocking the same, whereby the teeth thereof will be caused to engage the projections from said denominational wheels as the shaft supporting the denominational wheels is rotated, whereby the numerals on said denominational wheels will be brought into line and consequently restored.

27. In a computing mechanism, a series of denominational members, carrying mechanism therefor, resetting mechanism for said carrying mechanism, a stop rigidly secured to each of said denominational members, and a shaft loosely projecting through said denominational members for rotatably supporting the same, said shaft being formed with a notch, means for rotating said shaft when it is desired to restore said denominational members, a comb-like structure arranged in said notch formed with a body and with teeth projecting therefrom, a friction disk, said friction disk being formed with a pair of notches, a spring-pressed pawl normally engaging one of said notches adapted to press against the periphery of said friction disk when rotated, said friction disk being formed with an operating notch and said comb-like structure being formed with a projection fitting into said operating notch whereby when said shaft is rotated, the rotation of said friction disk will be delayed until said projection can move pivotally from one side of the notch to the other and thus rock the teeth on said comb-like structure so as to bring the same into the path of movement of the projection extending from the denominational members and thus collect said projections and restore the denominational members.

28. In a computing mechanism, a series of denominational wheels formed with lugs thereon, carrying mechanism for said denominational wheels, resetting mechanism for said carrying mechanism, a shaft loosely engaging said denominational wheels for supporting the same, said shaft being formed with a notch, means including a train of gearing for rotating said shaft nine-tenths of a revolution in one direction and then nine-tenths of a revolution in an opposite direction, a comb-like structure formed with 65 teeth, said comb-like structure being ar-

ranged in the notch of said shaft, and means for actuating said comb-like structure so as to cause the teeth thereof to move out of said shaft during the rotation thereof to engage the lugs on said denominational wheels for 70 restoring the denominational wheels as the comb-like structure and the shaft rotate and for moving the teeth of said comb-like structure into said notch upon a reverse movement of said shaft.

29. In a computing mechanism, a series of denominational wheels, carrying mechanism therefor, resetting mechanism for resetting said carrying mechanism, and means for restoring said denominational wheels, said means comprising a pivotally mounted handle, a segmental rack, means for connecting said handle and said rack so as to allow said handle a partial independent movement for resetting said carrying mechanism and then a simultaneous movement with the rack whereby the carrying mechanism will be reset and the denominational wheels will be restored, a train of gearing set in motion by said rack, a gear wheel rotated by said train of gearing, a shaft rigidly connected with said gear wheel, and means actuated by said shaft engaging said denominational wheels for restoring the same when the shaft is rotated in one direction.

30. In a computing mechanism, a series of denominational members formed with stops thereon, carrying mechanism for said denominational members, resetting mechanism for said carrying mechanism, and restoring means operable independent of said carrying mechanism and said resetting mechanism, said restoring means including a pivotally mounted handle, a rotating shaft, means for connecting said handle and said shaft whereby when said handle is moved pivotally said handle will be rotated, and a pivotally mounted comb set in motion by said shaft when rotated in one direction 105 adapted to engage said stops for collecting and restoring said denominational members.

31. In a computing device, a series of denominational wheels, each of said denominational wheels being formed with an enlargement thereon, carrying mechanism for said denominational wheels, said carrying mechanism including a pivotally mounted trip actuated by said enlargement, a transfer lever for engaging the next higher denominational wheel, and rotating the same a predetermined distance, a driver for moving said lever forwardly, means extending from said transfer lever into engagement with said trip whereby said trip will move 125 said transfer lever pivotally substantially simultaneously with its forward movement whereby the transfer lever is brought into engagement with the denominational wheels and moved for rotating the denominational 130

wheels, means for resetting said carrying mechanism, and means operable independent of the resetting means for restoring said denominational wheels.

32. In a computing machine, a series of denominational members, a transfer lever for each denominational member except the highest, a driver for each of said transfer levers, means for pivotally mounting the respective transfer levers on the respective drivers, whereby the transfer levers are moved toward the denominational members upon the release of the respective drivers, a trip lever for each of said denominational members, said trip levers being operated by said denominational members, a member connected with each of said transfer levers and engaging said trip levers for moving the transfer levers pivotally as the trip levers are moved by said denominational members, and means acting on said drivers for moving the drivers and the transfer levers simultaneously with the swinging of the various levers by the trip levers.

33. In a computing mechanism, a series of denominational members, a transfer lever for each of said denominational members except the highest, a trip lever for each of said transfer levers actuated by one of the denominational members of a lower order for causing said transfer lever to move one of the denominational members of a higher order, a pin extending from said trip lever to said transfer lever for swinging the transfer lever, and a spring pressed driver released by said trip lever simultaneously with the swinging of said transfer lever, whereby said transfer lever is adapted to engage said denominational members and move the same a predetermined distance.

34. In a computing mechanism, a series of denominational members, pivotally mounted trip levers operated by said denominational members, each of said trip levers having a slot therein, a spring pressed driver for each of said trip levers, a transfer lever pivotally mounted on each of said drivers, a pin carried by each of said transfer levers extending into the slots in said trip levers, whereby whenever said trip levers are tripped said transfer levers will be swung to one side,

and means carried by each of said trip levers for releasing said drivers simultaneously with the swinging of said transfer levers.

35. In a computing mechanism, a series of denominational wheels adapted to rotate in either direction, a carrying mechanism therefor including a pivotally mounted trip adapted to be tripped in either of two directions, a spring pressed driver, a pivotally mounted transfer lever arranged on said driver, means for loosely connecting said transfer lever and said trip, whereby when said trip is swung to either side of the neutral position said transfer lever will be swung to the same side of said neutral position, whereby said denominational members will be rotated according to the direction of swinging of said transfer lever for adding or subtracting, and means operated by said trip lever for releasing said driver simultaneously with the swinging of said transfer lever, whereby said transfer lever is moved forwardly and swung pivotally to one side substantially simultaneously.

36. In a computing mechanism, a series of denominational members, a pivotally mounted trip adapted to be operated by said denominational members, said pivotally mounted trip having a plurality of notches on one edge, a spring pressed locator formed with a projection fitting into one of said notches for holding said trip lever in any of its respective positions, and for resiliently resisting movement therefrom, a spring pressed driver, a pivotally mounted transfer lever mounted on said driver adapted to be moved bodily toward said denominational members by said driver, means extending from said transfer levers into engagement with said pivotally mounted trip lever, whereby said transfer levers are moved pivotally, substantially simultaneously with the tripping of said trip levers, and means operated by said trip levers for releasing said driver.

In testimony whereof I have signed my name to this specification in the presence of two subscribing witnesses.

JESSE V. SOUDER.
